UNITED STATES PATENT OFFICE

2,101,001

BUILDING CONSTRUCTION

Bruno E. Balduf, Chicago, Ill., assignor to United States Gypsum Company, Chicago, Ill., a corporation of Illinois

Application February 23, 1935, Serial No. 7,702

15 Claims. (Cl. 72—118)

This invention relates to building constructions and has reference more particularly to wall board attachments to building structures.

In attaching wall boards, such as those of gypsum composition with paper cover sheets, fiber boards, metal sheets, or other building units, it is desirable that any attaching means used be flush with the exposed surface of the boards so that said boards may be decorated with a plastic paint, 5 wall paper, etc., to completely conceal said attaching means. It is preferable but not essential to have the connection between the wall boards and a frame member of a resilient or yielding nature so that slight relative movement between the 10 boards and the frame members is permitted without cracking the decorative layer and to provide sound insulation.

An object of the invention, therefore, is to provide a means for attaching wall boards to frame 20 members, said attaching means lying flush with the exposed surface of the board to be completely concealed by the decorative coating on the boards.

Another object of the invention is to provide a 25 resilient connection between wall boards and frame members in which screws are used to connect said boards or units to the attaching means which preferably consists of perforated metal; also to improve building constructions in other respects hereinafter specified and claimed.

30 Reference is to be had to the accompanying drawings forming a part of this specification, in which

Fig. 1 is a perspective sectional view showing the improved wall and ceiling construction,

35 Fig. 2 is a perspective view of a resilient clip and perforated plate used in the construction shown in Fig. 1.

Fig. 3 is an elevation of the improved structure shown in Figs. 1 and 2,

40 Fig. 4 is a perspective sectional elevation showing a modified form of building construction utilizing metal studs.

Fig. 5 is a sectional plan view through the 45 structure shown in Fig. 4,

Fig. 5A is a sectional elevation through a modified form of resilient clip for attachment to special metal joists.

Fig. 6 is a sectional plan view taken at the 50 intersection of two partitions,

Fig. 7 is a perspective sectional view showing a modified form of construction in which boards are resiliently attached to metallic ceiling runners,

55 Fig. 8 is a sectional view through a modified

form of non-resilient attachment for walls and ceilings.

Fig. 9 is a modified form of wall construction in which the boards are attached to perforated plates by cementitious material. 5

Fig. 10 is a perspective sectional elevation of a further modified form of studless partition construction,

Fig. 11 is a perspective sectional elevation of a modified form of ceiling attachment for the partition shown in Fig. 10. 10

Fig. 12 is a sectional perspective view of a modified form of building structure in which boards are attached to perforated plates which in turn are attached to steel studs. 15

Fig. 13 is a perspective sectional elevation of a still further form of partition structure in which boards are attached to metallic studs having perforated flanges,

Fig. 14 is a sectional plan view through two intersecting partitions using box spacers, and 20

Fig. 15 is a perspective view of a connecting clip for the box spacers shown in Fig. 14.

Referring to the drawings by numerals, wooden studs 10 extend vertically in the usual manner in spaced, parallel relation, being connected at the top by a plate 11 on which ceiling joists 12 are secured. In order to resiliently connect wall boards 13 to the studs 10 and joists 12, I provide spring loops 14, one end of each loop being reverse bent to form a section 15 which is provided with a perforation 16 arranged to receive an attaching nail 17. An outstanding flange 18 is formed on the inner end of the section 15 to embrace the corner of the studs or joists to provide lateral stability. The opposite end of loop 14 is formed into a flange 19 which extends through struck out straps 20, 21, and 22 formed in a plate 23. The plate 23 has most of its outer area provided with closely spaced perforations 24 and 25 outstanding stiffening flanges are formed along the longitudinal edges of said plate. A locking flange 26 is provided in the plate 23 to be bent up into locking position after the flange 19 and plate. One of the salient features of my invention lies in the simple and efficient manner of attaching the boards 13 to the resiliently held perforated plates 23. In order to accomplish this attachment, I punch or drill a hole through the board to receive the screw 17, or other driven fastening element, the latter finding one of the perforations 24 in the plate and engaging in the same. The head of the screw sinks into the board to present a flush surface which may be puttied smooth, and then the exposed surface of the 35

40

45

50

55

board is provided with a decorative coating such as plastic paint, wall paper, etc.

In the form of the invention shown in Figs. 4 and 5, steel channel studs 27 are employed, said studs having a flange 28 extending along each longitudinal edge. A clip 29 extends across the web of stud 27 and is provided with arcuate loops 30 bent outwardly to form flanges 31, said flanges being then formed into resilient loops 32 terminating in flanges 33. Perforated plates 23 engage the flanges 33 in a manner hereinabove described. The clip 29 is snapped into position on the stud 27 with the flanges 27 seating between the loops 30 and 32.

15 When wall boards meet at an angle at a corner of a room as seen in Fig. 6, the flanges 25 of the plate 23 are clipped in the center and the plate 23 is then bent at an angle to register with the boards 13. Screws 17 then pass through the board and engage the plate perforations 24 so as to firmly connect the boards one to the other.

As seen in Fig. 5A, a channel shaped sheet metal joist 34 having inturned flanges 34a supports a resilient ceiling clip 34b. One end of clip 34b is return bent to form a flange 34c which hooks over the lower flange 34a. An L-shaped strip of metal 34d is spot welded to clip 34b and flange 34, said strip having a flange 34e which engages below the joist to hold the clip firmly in place. A perforated plate 23 is attached to the clip 34b in a manner hereinabove described.

In the form of the invention shown in Fig. 7, fiber boards 35 or other building sheets, are attached to perforated plates 23 by means of short screws 36 whose heads are positioned at the back of the plate, the screws being of insufficient length to pass completely through the board. This form of construction may also be modified as shown to resiliently attach to ceiling runners or channels 37 by means of the spring clips 14 which terminate in a hook 38 at their upper ends which engage the upper flange 39 of channel 37, thus forming a ceiling construction. If desired a non-resilient connection may be used as shown in Fig. 8 in which a clip 40 has a laterally extending extension 41 which engages the perforated plate 23 as previously described. A hook 42 is formed on the upper end of clip 40 for engaging a flange 43 of a channel runner 44 whose web, in this case, may extend parallel to boards 45 which are attached to perforated plate 23 by means of screws 46.

In the form of the invention shown in Fig. 9, a perforated plate 48 is attached to a masonry wall 49 of concrete or the like, with a stub nail 50 which is driven through said plate 48 into the face of the wall. Cementitious material 51, such as gypsum gauging plaster is then applied to the face of plate 48 and boards 52 are pressed onto the cementitious material 51, which after setting, firmly attaches the boards 52 to the wall 49.

The form of invention illustrated in Fig. 10 is a studless partition which can conveniently be 65 loosely assembled at the factory and shipped to the job for quick erection. A pair of boards 54 is attached together in spaced parallel relation with box-like, metallic spacers 55 intervening. Two opposed faces 56 of the members 55 are perforated to receive board attaching screws 57. These spacers 55 are positioned at suitable intervals over the faces and edges of the boards to cause said boards to act together as a beam and thus produce a rigid partition. The top and bottom 75 edges of the boards 54 are attached together

by means of horizontal channels 58 and 59 which may be nailed through holes 60 to the floor and ceiling respectively. Flanges 61 formed on channels 58 and 59 are perforated to receive the board attaching screws 57. Instead of channels 58 and 59, box spacers 61 (Fig. 11) may be provided with outstanding ears 62 at their upper end, each ear being provided with a nail hole 63 for nailing attachment to the floor or ceiling. Instead of perforated box spacers 55, wooden blocks 55a may be used. On unusually high partitions where greater rigidity is needed, a steel angle 55b may extend downwardly through a plurality of the spacers 55 at the joint between boards. Where two partitions intersect at right angles, two of 15 the box spacers 55 may be joined in edge to face relation at top and bottom by U-shaped spring clip 55c, the boards being attached to the box spacers 55 by screws in the usual manner. This construction permits pipes or electrical conduits 20 to be passed through the partition in any direction without interference from studs.

In the form of invention shown in Fig. 13, the channels 58 and 59 are used as studs 65 with boards 45 secured in edge abutting relation to 25 perforated stud flanges 66 by screws 67. In Fig. 12, I illustrate a modified form of wall construction in which perforated plates 68 are spot welded, or otherwise secured to flanges 69 of channel studs 70. Boards 45 are then secured to plates 30 68 by screws 67 in the manner described for Fig. 13.

I would state in conclusion that, while the illustrated examples constitute practical embodiments of my invention, I do not wish to limit myself precisely to these details, since manifestly the same can be considerably varied without departing from the spirit of the invention as defined in the appended claims.

Having thus described my invention, I claim as 40 new and desire to secure by Letters Patent:

1. A resilient clip structure for building constructions, comprising a resilient loop, a perforated plate associated with one end of said loop and adapted to receive board attaching screws, 45 said plate having closely spaced perforations the edges of said perforations being adapted to act as threads for said board attaching screws, and means on the other end of said resilient loop for attachment to a building frame.

2. A resilient clip structure for building constructions, comprising a resilient loop, a plate having closely spaced perforations and associated with one end of said loop and adapted to receive board attaching screws, the edges of said perforations being adapted to act as threads for said board attaching screws, an outstanding stiffening flange formed on said plate, and means on the other end of said resilient loop for attachment to a building frame.

3. A resilient clip structure for building constructions, comprising a resilient loop, a plate having closely spaced perforations and having struck out straps for receiving one end of said loop, said plate being adapted to receive board attaching screws, the edges of said perforations being adapted to act as threads for said board attaching screws, and means on the other end of said loop for attachment to a building frame.

4. A resilient clip structure for building constructions, comprising a resilient loop, a plate having closely spaced perforations and having struck out straps for receiving one end of said loop whereby the plate is supported thereon, said plate being adapted to receive board attaching 75

5 screws, the edges of said perforations being adapted to act as threads for said board attaching screws, a locking flange associated with said plate and adapted to be bent into locking engagement with said loop to retain said plate on said loop end, and means on the other end of said loop for attachment to a building frame.

5. A resilient clip structure for building constructions comprising a resilient loop, a plate 10 having a multiplicity of closely spaced perforations, said plate being supported on one portion of said loop and adapted to receive board attaching screws, the edges of said perforations being adapted to act as threads for said board attaching screws, another portion of said loop being 15 perforated for nailing attachment to a wooden frame member.

6. In a building construction, a perforated plate of substantially small area and having a 20 multiplicity of closely spaced perforations, wall boards arranged in a plane substantially parallel to said plate with edges substantially abutting, screws passing through said boards and engaging in the perforations in said plate, the edges 25 of said perforations being adapted to act as threads for said board attaching screws, and means for securing said plate to a building structure.

7. In a building construction, an L-shaped 30 plate having a multiplicity of closely spaced perforations, wall boards arranged at an angle with their adjoining edges lying adjacent the apex of said plate, and screws passing through said boards and in binding retaining engagement 35 in the perforations in said plate, the edges of said perforations being adapted to act as threads for said board attaching screws.

8. In a building construction, a channel runner 40 having opposed flanges and a web, a clip having a hook at one end adapted to engage one of said flanges, a perforated plate secured to the opposite end of said clip, boards in face abutting relation to said plate, and screws extending into said boards and engaging the metal of the plate 45 at the perforations in said plate to secure said boards to said plate.

9. In a building construction, a channel runner having opposed flanges and a web, a clip having a resilient loop and having a hook at one 50 end adapted to engage one of said flanges, a perforated plate secured to the opposite end of said clip, boards in face abutting relation to said plate, and screws extending into said boards and engaging the metal of the plate at the perforations in said plate to resiliently attach said 55 boards to said runner.

10. In a partition structure, a channel stud having a web and flanges, boards lying in edge abutting relation against said stud, said stud being provided with a multiplicity of closely spaced perforations, and screws passing through said 5 boards and engaging said perforations to connect said boards to said stud, the edges of said perforations being adapted to act as threads for said board attaching screws.

11. In a building construction, a channel stud 10 having a web and flanges, a plate secured to said stud, said plate being provided with closely spaced perforations, a board having the inner face thereof abutting against said plate, and screws passing through said board and engaging 15 in said perforations to connect said board to said channel, the edges of said perforations being adapted to act as threads for said board attaching screws.

12. The method of attaching building boards 20 to a perforated plate having closely spaced perforations, which comprises positioning said board in face abutting relation against said plate, forcing a punch through said board into a registering perforation in said plate, withdrawing said 25 punch to leave a hole in said board, and causing a screw to enter said hole and engage in the registering perforation in said plate so as to pull said board tightly against said plate.

13. In a building construction, a perforated 30 plate having a multiplicity of closely spaced perforations, a building board in face abutting relation against said plate, and a screw passing through said board and engaging in one of the 35 perforations in said plate, said perforations being arranged to direct said screw into retaining engagement in one of said perforations.

14. In a building construction, a plate having a multiplicity of closely spaced perforations, wall boards having edges adjoining adjacent said 40 plate, and screws passing through said boards and engaging in the perforations in said plates, said perforations being arranged to direct said screw into retaining engagement in one of said perforations.

15. In a building construction, a strip having a multiplicity of closely spaced openings, a wall panel in face abutting relation against said strip, and a driven fastening element passing through said panel and engaging in one of said openings 50 so as to attach said panel to said strip, said openings being arranged to direct said fastening element into retaining engagement in one of said openings.

BRUNO E. BALDUF. 55
